UNITED STATES PATENT OFFICE.

CHARLES F. KRAUT, OF BRIDGEPORT, CONNECTICUT.

SAFETY VALVE.

Application filed February 2, 1924. Serial No. 690,159.

To all whom it may concern:

Be it known that I, CHARLES F. KRAUT, citizen of the United States, residing at Bridgeport, in the county of Fairfield and 5 State of Connecticut, have invented certain new and useful Improvements in Safety Valves; and I do hereby declare the following to be a full, clear, and exact description of the invention, such as will enable others 10 skilled in the art to which it appertains to make and use the same.

This invention relates to safety valves and is an improvement on the patent granted to me on July 9, 1918, No. 1,271,726.

15 The present application has for its object the construction of a safety valve which will pop without a preliminary simmer, and lift to its maximum capacity, and which can be adjusted to close from two to five pounds 20 below the pressure for which it has been set to pop. This is accomplished by attaching a hood to the valve seating member which coacts with a double control adjusting ring. It is evident that as this ring is raised it 25 confines the steam in an inside steam passageway and the hood, thus forming a popping chamber similar in function to an outside popping chamber formed by the valve disc and the lower portion of the double con- 30 trol adjusting ring.

A further object of the hood is to prevent dirt, grit, or cinders from sifting down on the valve seating member, as this would seriously interfere with the proper working of 35 this type of valve.

Various other objects and advantages of the invention will be pointed out in the detailed description appearing hereafter, and in order that the same may be better understood 40 reference is had to the accompanying drawings forming a part of this specification.

In the drawings—

Figure 1 represents a vertical section of 45 the improved valve, partly in section;

Figure 2 is an upper plan view of the confining hood and double control adjusting ring, sectional view of the valve seating member and spring on line 2—2 of Figure 1;

50 Figure 3 is a partial plan view of the floor of the confining hood, sectional view of the valve disc guide, on line 3—3 of Figure 1;

Figure 4 is a detail view of the valve disc, valve disc guide, and broken view of the 55 valve seating member;

Figure 5 is a broken partial plan view of the base of the valve, and a partial plan view of the double control adjusting ring;

Figure 6 is a detail elevation of the double control adjusting ring; 60

Figure 7 is a broken sectional view of the relative position of the several elements while the valve is discharging, and

Figure 8 is a detail broken sectional view of the valve disc, hood, and double control 65 adjusting ring.

1 represents the valve base, preferably disposed vertically and having a steam passage 2 threaded at its inlet and for attachment to a boiler. 3 is a guide integrally joined to the base by webs 4, Figures 1 and 5. The intervening space forming the steam ports 5 surrounded by the circularly arranged raised valve seats 6 corresponding to the raised portions 7 of the valve disc 8. 70

The valve seating member 9 has its lower end guided in the recess 10, Figure 1, and its upper end guided in the cylindrical wall 11 depending from the dome 12. 13 is the valve spring controlled by the adjusting 80 screw 14.

The valve disc guide comprises the rim 15 joined to the valve seating member 9 by the webs 16, Figures 1, 3, and 7. The intervening spaces between the webs forming the 85 inside steam passages 17, seen more clearly in Figure 3. The base of the rim and webs conform to the curved portion 18, Figure 8, of the valve disc and thus form a ball seat contact therewith. This ball seat contact assures automatic alignment and the proper seating of the valve disc on the raised seats 6. 90

19, Figures 1, 5, and 7, is a double control adjusting ring mounted on the base 1. The 95 ribs 20 divide the ring into the outside steam passages 21, see also Figure 6. The circularly arranged teeth 22 of the ring serve, in connection with the stop pin 23, Figures 1 and 7, to maintain said ring in any of its 100 adjusted positions.

24 is a hood adjustably mounted on the valve seating member 9, Figures 1, 2, and 7. This hood forms the popping chamber 25 and temporarily confines the steam therein, Figures 1 and 7, and acts in conjunction with the popping chamber 26 located below the valve disc and between said disc and the inner wall of the double control ring 22. 105 The hood also serves as an umbrella prevent- 110

ing dirt, grit or cinders sifting down into the recess 10, thus insuring free movement of the lower end 27 of the valve seating member 9 therein. 28 is a circularly arranged floor closely embracing the valve disc guide 15 and is connected to the hood by the webs 29, Figures 1, 3, and 7.

30 is an inside muffler adjustably mounted on the depending wall 11 of the dome and 10 is provided with the openings 31 operating in connection with the openings 32 of the dome to prevent the steam escaping in volume.

In Figure 1, the valve is shown seated 15 and all of the other elements are in their normal position. It will be observed that there is a narrow space α , shown in Figure 8, between the upper end of the double control adjusting ring 19 and the hood 24 and an equal space between the corner b of the valve disc 8 and the lower edge c of the steam passage 21. These spaces or 20 openings determine the blow down or the reduction in pounds of the steam pressure, 25 and are under the control of the adjusting ring 19. In other words, the blow down period is increased or decreased proportionately as the area of these spaces vary.

When the valve disc 8 is unseated by the 30 excess boiler pressure the steam, see arrows, Figure 7, flows through the ports 5 and up through the inside passages 17, shown in Figure 3, into the popping chamber 25 of the hood 24, and also into the outside popping chamber 26 and through the passages 21 of the double control adjusting ring 19. The steam in chamber 25 flows downward and its force reacts on the floor 28 of the 35 hood to prevent the valve disc being unseated too long, thus allowing the same to close two to five pounds below the pressure for which it has been set to pop. The inclined face e , Figure 8, of the valve disc 8 permits the steam to flow freely through 40 the chamber 26 and also minimizes the seating resistance of the valve disc.

In cheaper constructions of the valve, the 50 inside muffler 30 could be dispensed with and the hood 24 mounted on the cylindrical wall 11 to serve the single purpose of an umbrella to prevent cinders, dirt, &c., clogging the valve seating member 9. In which case, it need not be adjustable.

What is claimed is:—

1. In a safety valve of the character described, a base, a muffler dome mounted thereon, said dome having a cylindrical wall depending therefrom, an inside muffler adjustably mounted thereon, said base having 55 circularly arranged steam inlet ports, a valve disc therefor, a valve spring, a valve seating member, a hood adjustably mounted thereon to form a popping chamber, said

hood having a floor depending therefrom, 60 said valve seating member having a valve disc guide with a ball seat contact with the valve disc, said valve disc guide having steam passages therethrough and communicating with the interior of the hood and the steam inlet port, and a double control 65 adjusting ring having steam passages therethrough.

2. In a safety valve of the character described, comprising a base, a double control adjusting ring mounted thereon, a valve 70 disc seating member, a hood mounted on said member, said valve disc and hood co-acting with said double control adjusting ring to control the steam escaping from two steam passageways located above the valve 75 disc.

3. In a safety valve of the character described, comprising a base having steam 80 ports, a valve disc therefor, a valve seating member having a base, a valve spring 85 having its lower end in ball contact with the base of the valve seating member, said valve seating member having a circumferentially arranged valve disc guide in ball contact with the disc valve.

4. In a safety valve of the character described, a base having steam inlet ports, a valve disc therefor, a valve seating member, a hood adjustably mounted thereon, said valve seating member having a valve 90 disc guide, and having steam passages therethrough opening into the hood, said hood having a circumferentially arranged floor projecting inwardly therefrom and upon which the steam reacts.

5. In a safety valve of the character described, comprising a base having steam inlet ports, a valve disc therefor, a valve seating member having a valve disc guide engaging the valve disc and having steam 105 passages therethrough, a hood adjustably mounted on the valve seating member, overhanging the valve disc and valve disc guide and forming a steam confining chamber.

6. In a safety valve of the character described, a base having steam inlet ports, a valve disc therefor, a valve seating member having a valve disc guide in contact with the valve disc, a hood adjustably mounted on the valve seating member and overhanging the valve disc guide and valve disc, said valve disc guide having openings therethrough to form inside steam passages to admit steam under the hood, and a double control adjusting ring having openings 110 therethrough to form outside steam passages to act in conjunction with the said inside steam passages.

In testimony whereof I affix my signature.

CHARLES F. KRAUT.
